UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed May 22, 1924. Serial No. 715,026.

To all whom it may concern:

Be it known that I, ALFRED G. F. KUROWSKI, a citizen of the United States, residing in Brooklyn Borough, in the county of Kings, city and State of New York, have invented certain new and useful Improvements in Typewriting Machines, of which the following is a specification.

This invention relates to typewriting machines, with particular reference to the manner of limiting the endwise movements of their carriages in both directions by marginal stops.

The marginal-stop bar is usually angular in cross-section having square-cut teeth spaced in accordance with letter-space distances and scaled at intervals in conformity with a paper-scale at the front of the machine.

Mounted to slide on the bar to adjustably engage its teeth are marginal-stops, one of which may be set to indicate a point for the initial character at the commencement of each line, with key-board release for marginal notations; the other stop operates a bell in advance of a predetermined position, thereafter locking the printing elements upon reaching such position, and by the key-board release permitting one or more characters to be printed, as a syllable or part thereof, after the predetermined stop position has been reached.

To accomplish these purposes one of the features of the present invention comprises a marginal-stop, formed of a single piece of sheet-metal folded into rectangular shape, its edges abutting to constitute a box-like structure enclosing the stop bar on four sides and having an inreaching tooth engageable in any of the tooth spaces in the bar, and also having a downwardly bent projection on its underside engageable with a fixed carriage stop.

The wall of the marginal stop opposite the tooth-carrying side is flared outwardly, providing a housing for a spring normally holding the tooth in an engaged position but readily yielding to permit retraction of the tooth when the stop is shifted to a new position and it is to be noted that the marginal stop body is of integral construction, readily and inexpensively produced by punching and die-forming methods which also assure uniformity of product.

Another feature is to utilize the marginal-stop bar for the double purpose of adjustably supporting the marginal stops and also the column or tabulating stops, thereby dispensing with a separate bar for the latter purpose, saving the expense and weight thereof.

Other features and advantages will hereinafter appear.

In the accompanying drawings,

Figure 1 is a longitudinal vertical sectional view at the center of the machine.

Figure 2 is a rear elevational view of the upper portion of the carriage, showing the marginal stops and line-locking mechanism.

Figure 3 is a plan view of the parts shown in Figure 2.

Figure 4 is a side view, largely diagrammatic, showing the releasing connections for the marginal-stop, the general outline of the machine frame appearing in broken lines.

Figure 5 is an enlarged fragmentary front view of the lower left-hand corner of the machine.

Figure 6 is an enlarged view of the two marginal-stops as mounted upon a stop-bar, looking from the rear.

Figure 7 is a plan view of the parts shown in Figure 6.

Figure 8 is a transverse sectional view taken on line 8—8 of Figure 7, showing the right-hand marginal-stop.

Figure 9 is a similar sectional view taken on line 9—9 of Figure 7, showing the left-hand marginal stop.

Figure 10 is a diagrammatic view illustrating the action of the marginal-stop on the bell-ringing and line-locking mechanisms.

Figure 11 is a detail view of the stop-lever shown by full lines in engaged position and by broken lines as in releasing the carriage for left-hand marginal notations.

Figure 12 is an enlarged perspective view of a marginal-stop spring.

In the drawings, a plurality of key-levers, designated generally by the numeral 20, are shown as arranged in banked relation, constituting a key-board, each lever operating a bell-crank 21, pivoted upon a fulcrum rod 22, and adapted to pull a link 23, operating to force a type-bar 24 from its

resting pad 25, to strike the face of a cylindrical platen 26, the same being mounted to rotate upon an axle 27, housed within bearings at the carriage-ends 28.

- 5 These carriage-ends are rigidly joined together by a base plate 29 formed with runways 30 at its longitudinal edges, which co-operate with similar runways 31 and 32, fixed adjustably to the carriage-shift frame, 10 anti-frictional elements 33 being disposed between the adjacent runways.

- A carriage feed-rack 34 normally controls the movement of the carriage in one direction, the feed-rack having arms 35 15 pivotally hung as at 36, to each carriage-end and being spring-pressed into engagement with a pinion 37 forming part of an escapement wheel 38.

- This escapement wheel is mounted on a 20 back-plate 39 of the carriage-shift frame, and provided with the usual escapement rocker and dogs 40 which are actuated by an interponent 41 mounted upon a swinging frame 42, the frame being operated by a universal bar 43, moved rearwardly by type-bar contact a little in advance of type contact with the platen, thus intermittently releasing the carriage to be moved in a letter-space 25 direction by a tape drawn by a spring-motor 30 44 mounted on the back-plate 39.

- The carriage-ends 28 have inreaching flanges 45 supporting angular arms 46, held 35 adjustably by screws 47, the rear ends of the arms being bent at a right angle to align a marginal-stop bar 48 held fast by screws 49.

- The stop-bar 48 extends across the rear 40 of the carriage, between the end plates 28 and is provided with rack-teeth letter-space distances apart and also with indicia corresponding to the reading of a scale and 45 pointer (not shown) at the front of the platen.

- Marginal-stops, generally denoted by the numerals 50 and 60, control the carriage 45 movement towards the left and right hand respectively, these stops being similar in shape but reversed, each being formed completely from a single piece of sheet metal.

- The stop 50, shown in Figures 6, 7 and 50 9, presents a rectangular box-like slide suited to bear on three sides of the stop-bar 48, the edges of the folded metal abutting along the center at the under side.

- Formed on the straight wall 51 of the 55 stop 50, is a sharply bent, inreaching detent or tooth 52, engageable in any of the tooth spaces in the adjacent side of the bar, co-acting with them in resisting any force applied to the stop in a plane parallel with 60 the bar.

- The opposite wall 53 of the stop is flared 65 outwardly providing a wedge-shaped housing, between it and the bar 48, to receive a flat compression spring 54 one of its leaves 55 having plain parallel side edges presented

outwardly against the wall 53 and the other leaf 56, adjacent the bar, having lugs 57 on both side edges near its ends to interlock with the four edges of the stop, preventing detachment of the spring when the stop is 70 assembled on the bar.

The lower wall at the flared end of the stop 50 is bent downwardly at a right angle forming an abutment 58, its inner edge extending below the center of the bar, as shown 75 in Figures 6 and 9.

The indexing edge of the stop may be swedged to form a bevelled face 59 for convenience in setting the stop to a scale reading on the bar, and the rear face of the 80 stop knurled to promote shifting the same.

As shown by the broken lines in Figure 85 7, pressing the rear face 53 of the stop towards the stop-bar causes the entire stop to rock, swinging the detent 52 out of engagement with the teeth of the bar; during such disengagement the stop may be moved in either direction along the bar, and upon releasing the finger pressure, the spring elements will restore the detent into locking 90 relation with the adjacent space between the teeth of the bar.

The stop 60 is folded oppositely to the stop 50 and has formed on its under side a depending longitudinal flange 61 bent at 95 its inner end at a right angle to provide an abutment 62 capable of arresting the carriage when thrust to the right hand for a new line.

The stops 50 and 60 have their respective 100 abutments 58 and 62 extended below the bar 48 on opposite sides in two different vertical parallel planes for purposes presently appearing.

The rear fixed carriage rail or runway 105 32 has at its upper edge an extension 65, forming a seat for an apron 66 having ledges 67 secured by rivets 68 to the extension, thus rendering the apron substantially a 110 part of the carriage shift frame.

A carrier 69 is pivotally mounted on a shouldered stud fixed in the apron 66 and provided with a retaining screw 70; a spring 71 is coiled about the stud, its ends being engaged in such manner as to press the carrier 115 against a stop 72 on the apron.

The lower end of the carrier 69 has secured to it a wire terminating in a hammer 73 arranged to strike a bell 74 secured to the back-plate 39. The upper end of the carrier supports a pivoted trip 75, actuated by a spring 76 arranged to press an offset portion of the trip against the adjacent edge of the carrier.

The stop 50, in moving in the direction of the arrow (see Figure 2), will collide with the trip 75 and turn the carrier 69 into the position shown in Figure 10, eventually releasing the trip, allowing the hammer 73 to fall, striking the bell as a signal to the oper- 125 130

ator that only a limited number of characters can thereafter be printed upon a line.

When the stop 50 is moved in a reverse direction, as for the commencement of a new line, the abutment 58 will engage the opposite side of the trip, causing it to turn upon its axis and pass idly under the abutment to be restored by the spring 76 after passage of the stop.

10 After releasing the trip 75 and warning conveyed by the bell, the machine will continue to operate for usually five letter-space distances, whereupon the stop 50 will contact with a carriage lock-stop 77 which will be moved along by it until all further movement is prevented by the locking of the keyboard, the accomplishment of which will now be explained.

The lock-stop 77 is a projecting part of a slide lever 78 having a slot 79 midway its length through which passes a fixed supporting stud 80, the lever being further guided longitudinally by a slot 81 at its inner end engaged with a fixed pin 82.

25 An offset element 83, at the inner end of the lever 78, is guided within a slot in a ledge 84 formed on the lower edge of the apron 66 and drawn to the left by a tension spring 85 attached at its ends respectively to the offset and apron, the sliding movement of the lever being limited by the slot 79.

The outer right-hand end of the lever 78 is bent at a right angle forming a pad 86 abutting the curved facial edge 87 of a lever 88, pivoted at 89 to the rear side of the back-plate 39, and extending downwardly to a point adjacent the lower edge of a frame 90.

The lower end of the lever 88 is bent towards the front of the machine, as at 91, to contact with a pin 92 projecting upright from the horizontally disposed lever 93, pivoted on a stud 95 and extending to the front of the machine, where its forked end engages a pin 96, fixed in a bracket 97 secured to a key-lever lock plate 98.

50 The plate 98 is arranged to slide lengthwise against the rear side of a front comb plate 99 upon studs 100 passing through slots 101 in the comb plate, limiting relative movement.

As shown on Figure 5 the comb plate 99 guides the key-levers 20 and the lock-plate 98 has open topped slots registerable with the slots of the comb, in which position the plates are normally held by the tension spring 102, and the key-levers are free to operate.

When the lock plate 98 is shifted by the stop 50, acting through the several levers just described, it will be seen that the lock plate will effectively prevent use of the keyboard until the parts become restored to their normal positions.

65 A line-locking mechanism should be operated during a single letter-space distance

of the carriage movement, as otherwise a fast operator will pile up two characters at the line-locking position. As shown in Figure 10, the stop 50, in moving in the direction of the arrow a single letter-space distance, indicated by the broken lines, will shift the lever 78 in unison, causing the lever 88 to actuate the lever 93 and shift the lock-plate 98.

The square edges of the open slots in the lock-plate act as abutments to receive the key-levers 20, presenting an interference to the stroke of the key that is practically instantaneous in action.

When the carriage is shifted to upper case position, the lever 88 will be raised therewith but its lower end will still engage the pin 92 which is made sufficiently long for this purpose.

To co-operate with the right-hand marginal stop 60, a stop-lever 105, hung upon the fixed pivot 80, bears against the apron 66, a hub or collar 106 spacing the lever 105 from the adjacent parallel lever 78, this space being further maintained by a shoulder on the pin 82.

Formed on the inner or left-hand end of the lever 105, is a stop-tooth 107 shaped to engage with the stop 60 and a ledge 108, bent at a right angle from the lower edge 95 at the right hand of the lever 105, passes under the lower edge of the lever 78.

From the foregoing it will be understood that the levers 78 and 105, both oscillate about the same axis 80 and also in unison due to the pin-and-slot connection, that the lever 78 has a lengthwise movement independently of the lever 105, and that the effect of the spring 85 is to pull the lever 78 to a stop position defined by the slot 79, and also to swing both levers on the pivot 80 until seated on an abutment 109 formed at the lower edge of the apron 66.

As shown in Figure 11, the stop 60, when moved in the direction of the arrow, strikes the raised portion of the stop-tooth 107, which may be slightly undercut to co-operate with the angular face of the abutment 62 on the stop 60, to prevent the stop accidentally skipping the tooth 107 under severe impact.

When the stop 60 engages the stop-tooth 107 the carriage is at its initial position relative to the line of writing and if notations are required in the left-hand margin, the stop-tooth 107 must be released from the stop 60 to allow the carriage to be shifted in bringing the desired marginal position to the printing position.

To accomplish this purpose the lever 105 is oscillated to move its tooth 107 below the plane of the stop 60, by an arm 110 of a bell-crank, pivoted on a screw 111 set in the left-hand side of the carriage shift-frame and pressed against the ledge 103 by a

spring 112 coiled about the screw and having its ends in contact with the bell-crank and frame side respectively, as shown in Figure 4.

- 5 The other arm 113 of the bell-crank is pivotally connected with a push-red 114 extending to the front of the machine where it is pivoted to a lug 115 of a vertically disposed lever 116 mounted to oscillate upon a 10 screw 117 set into a part of the machine frame, and provided with a restoring spring 118, drawing the front corner 119 of the bottom of the lever into stop position with a seat 120 formed on an adjacent part of the 15 machine frame, this seat also co-operating with the lever to prevent it from being swung excessively rearward.

The upper front side of the lever 116 is provided with a push button 121 extending 20 through an opening in the front shield plate 122, parallel over the upper bank of keys.

Thus when conditions exist, as shown in Figure 11, by pushing the button 121, the intermediate connections cause the lever 105 25 to move to the broken line position, permitting passage of the stop 60, and when the carriage moves to the right of this figure, the stop 60 will engage the inclined face of the tooth 107, pressing it out of the path 30 of the stop and without moving any part of the mechanism except the two levers 78 and 105.

When the carriage is shifted to the line-locking position, as shown in Figure 10, the 35 button 121 may be pressed to oscillate the levers, causing the lever 78 to swing to the broken line position, releasing the stop 50, whereupon the spring 85 draws the lever 78 back to its normal position, restoring the 40 lever 88, thus withdrawing the locking plate 98, releasing the key-levers and allowing two or more characters to be printed, as in completing a syllable or word.

In addition to the use of the bar 48 for 45 adjustably supporting the marginal stops in any desired position, the bar may also be employed for supporting the adjustable tabulating stops 124, as shown in Figures 1 and 2.

50 The tabulating stops, when used, are invariably disposed in the space on the bar between the stops 50 and 60, and as their length precludes contact with the trip 75 or stop levers 78 or 105, no confusion or confusion can occur by the double use of the bar, while on the contrary a very decided economy is effected.

It will be understood that the column or 60 tabulating stops are suited to engage between the teeth of the bar 48, on opposite sides, are readily removed or replaced to obtain desired adjustment and when in such adjustment clear all parts of the mechanism except the stop 123, fixed on the machine to 65 be moved interceptingly into the path of

the tabulating stops by a tabulating key in a well known manner.

Variations may be resorted to within the scope of the invention, and portions of the improvements may be used without others. 70

Having thus described my invention, I claim:

1. In a typewriting machine, the combination with a rack-bar, of a pair of marginal stops, each comprising a slide shaped from a single piece of sheet metal to engage on three sides of the bar, the fourth side flaring outwardly presenting a wedge-shaped pocket adjacent one edge of the bar, an inreaching detent on the opposite side, and a transverse abutment on the lower side, said abutments extending equally below the bar and in opposite directions from the center thereof, and a spring in each pocket normally maintaining the detents in the tooth spaces of 80 said rack-bar.

2. In a typewriting machine, the combination with a rack-bar, of a pair of marginal stops, each comprising a slide shaped from a single piece of sheet metal to engage on three sides of the bar, the fourth side flaring outwardly presenting a wedge-shaped pocket adjacent one edge of the bar, the abutting edges of the slide meeting at the under side, centrally of the bar, a detent formed at the end of the wall opposite the flared side, and an abutment extending transversely downward from the opposite sides of the meeting edges to a uniform distance below said bar, and a bent flat spring 100 in each pocket to retain the detents in engagement with the teeth of said bar.

3. In a typewriting machine, the combination with a rack-bar, of right and left hand stops, each comprising a slide fitting 105 the bar at the top, bottom and rear, the front wall being spaced to present a triangular opening adjacent the bar, a detent on the rear wall for tooth engagement with the rack-bar, a transverse abutment on the lower wall, said abutments extending to a uniform distance below said bar and respectively to the right and left of its longitudinal center, and a reinforcement for the right hand abutment, all of said elements 110 being of integral construction, a bent flat spring in each pocket to retain the detents in engagement with the teeth of the rack-bar, and means on said springs to prevent shifting relatively to the slides. 115

4. In a typewriting machine, the combination with a rack-bar, of right and left hand stops, each comprising a slide fitting the bar at the top, bottom and rear, the front wall being spaced to present a triangular opening adjacent the bar, said slide being formed from a single piece of sheet-metal, the meeting edges of which abut centrally below the bar, a tooth-engaging detent on the rear wall, an abutment on the bottom 125 130

wall extending transversely from the meeting edge to the front of the left hand slide, and a flange on the rear abutting wall of the right hand slide, said flange being

5 turned at a right angle towards the rear wall constituting a transverse abutment, and being inclined angularly outward, and a flat spring in each slide opening, retaining the detents in engagement with the teeth of said

10 rack-bar.

5. In a typewriting machine the combination with a rack-bar, of right and left hand stops, each comprising a slide fitting the bar at the top, bottom and rear, the front wall 15 being spaced to present a triangular opening adjacent the bar, said slide being formed from a single piece of sheet-metal, the meeting edges of which abut centrally below the bar, a tooth-engaging detent on the rear 20 wall, and an abutment on the lower wall of each slide at their proximate ends, said abutments extending below the bar in relatively opposite directions, a flat spring bent to present opposed leaves suited to engage in the 25 triangular openings, and lateral lugs at the corners of one of the leaves to engage the ends of the upper and lower walls of each slide to be held in place thereby.

6. In a typewriting machine, the combination with a rack-bar, of right and left hand stops, each comprising a slide fitting the bar at the top, bottom and rear, the front wall being spaced to present a triangular opening adjacent the bar, said slide being formed 35 from a single piece of sheet-metal, the meeting edges of which abut centrally below the bar, a tooth-engaging detent on the rear wall, and an abutment on the lower wall of each slide at their proximate ends, said abutments extending below the bar in relatively 40 opposite directions, said slides being bevelled on their upper proximate edges directly over the rack-bar and knurled on their outer flared walls, wedge-shaped flat springs dis-

45 posed in the mentioned openings, and lugs on said springs engaging the ends of the slides, said springs being flexed by finger pressure to release the detents from engagement with the rack-bar.

50 7. In a typewriting machine, the combination with a shiftable carriage frame, fixed supports on the machine for said frame, a rack-bar fixed in said frame to carry adjustable tabulating stops, and a bell fixed on the machine frame, of a pair of marginal stops adjustable on said bar, a bell-crank lever pivoted to one of the fixed supports, a stop on the support, a spring drawing the lever against said stop, a trip-pawl pivoted 55 to said lever in the path of one of said marginal stops, said pawl oscillating the lever when moved by the marginal stop in one direction and yielding upon reverse movement of the marginal stop, means to restore 60 the pawl after passage of the marginal stop,

and a hammer carried by the opposite end of said lever to make contact with said bell when the lever is oscillated.

8. In a typewriting machine, the combination with a shiftable carriage frame having 70 fixed supports, a rack-bar in said frame, and a fixed bell, of a marginal stop adjustable on said bar, a bell-crank lever pivoted on one of the carriage frame supports, a trip-pawl pivoted to one end of said lever to engage said stop, said stop tilting the lever when moved in one direction and swinging the pawl inoperatively when moved reversely, a stop for said lever, a spring urging the lever into contact with the lever stop, and a hammer fixed to the opposite end of said lever to strike said bell upon oscillation of said lever.

9. In a typewriting machine, the combination with a shiftable carriage frame, fixed 80 supports on the machine for said frame, a rack-bar fixed in said frame to carry adjustable tabulating stops, and a bell fixed on the machine frame, of a pair of marginal stops adjustable on said bar, a bell-crank lever 85 pivoted to one of the fixed supports, a stop on the support, a spring drawing the lever against said stop, a trip-pawl pivoted to said lever in the path of one of said marginal stops, and to avoid the other, a lug on said pawl to engage the lever when the pawl is turned in one direction, a spring normally maintaining the lug against the lever to transmit movement upon contact with the support stop in one direction, said spring 90 yielding to permit the pawl to turn without transmitting motion to the lever when the marginal stop makes contact with the opposite edge of the pawl, and a hammer arranged to strike said bell upon oscillation 95 of said lever.

10. In a typewriting machine, the combination with a shiftable carriage frame, fixed supports on the machine for said frame, a rack-bar fixed in said frame to carry adjustable tabulating stops, and a bell fixed on the machine frame, of a pair of marginal stops adjustable on said bar, a bell-crank lever pivoted to one of the fixed supports, a hammer carried by said lever to strike said 110 bell when the lever is oscillated, a trip-pawl pivoted to said lever to oscillate the same when contact is made by the left hand stop against the pawl in moving towards the right, a spring normally holding said pawl in engaging position, said spring yielding when the stop strikes the pawl in moving toward the left, transmitting no action to the lever, and means for restoring said lever to its initial position after oscillation.

11. In a typewriting machine, the combination with a carriage frame having fixed supports, and a rack-bar to carry adjustable tabulating stops, of a pair of marginal stops adjustable on said bar, said stops being re- 125

spectively right and left hand, a bell-ringing device controlled by the left hand stop, and a line-locking device operated by said left hand stop at a predetermined number of letter-space intervals after actuation of the bell-ringing device.

12. In a typewriting machine, the combination with a carriage frame having fixed supports, and a rack-bar to carry adjustable tabulating stops, of a pair of marginal stops adjustable on said bar, said stops being respectively right and left hand, bell-ringing means actuated by the left hand stop, line-locking means operated by said stop a predetermined number of letter-space intervals thereafter, and key-operated means for releasing said line-locking means permitting completion of a line.

13. In a typewriting machine, the combination with a carriage frame having fixed supports, and a rack-bar to carry adjustable tabulating stops, of a pair of marginal stops adjustable on said bar, said stops being respectively right and left hand, a bell-ringing device controlled by the left hand stop, line-locking means operated by said stop a determinate letter-space distance thereafter, said means operating irrespective of the plane of the platen of the machine, means for restoring the line-locking means, the last-named means becoming operative upon the return of said rack-bar to its initial position, and a key-operated means for releasing said line-locking means at will.

14. In a typewriting machine, the combination with a shiftable carriage frame, fixed supports therefor, and a rack-bar in said frame, of marginal stops adjustable on said bar, said stops being respectively right and left hand, a stop-lever pivoted and limitedly slidable on the carriage frame support, said lever having a part disposed in the path of the left hand stop by which the lever is moved to the right upon contact therewith, the lever oscillating upon its pivot when contact is made in a reverse direction, a spring to restore said lever, and means actuated by the lever when moved to the right for locking the key-levers of the machine.

15. In a typewriting machine, the combination with a shiftable carriage frame, fixed supports therefor, and a rack-bar in said frame, of marginal stops adjustable on said bar, said stops being respectively right and left hand, a stop-lever pivoted and limitedly slidable on the carriage frame support, said lever having a part disposed in the path of the left hand stop by which the lever is moved to the right upon contact therewith, the lever oscillating upon its pivot when contact is made in a reverse direction, a spring to restore said lever, a stop limiting the action of said spring, a guide for the lever, means for locking the key-levers of the machine, and means actuated by said

stop-lever when moved to the right to operate said locking means.

16. In a typewriting machine, the combination with a shiftable carriage frame, fixed supports therefor, and a rack-bar in said frame, of marginal stops adjustable on said bar, said stops being respectively right and left hand, a stop-lever pivoted and limitedly slidable on the carriage frame support, said lever having a part disposed in the path of the left hand stop by which the lever is moved to the right upon contact therewith, the lever oscillating upon its pivot when contact is made in a reverse direction, a spring to restore said lever, means actuated by the lever when moved to the right for locking the key-levers of the machine, and means on the machine keyboard for oscillating said stop-lever out of the path of the stop.

17. In a typewriting machine, the combination with a shiftable carriage frame, fixed supports therefor, and a rack-bar in said frame, of a marginal stop adjustable on said rack-bar, a stop-lever pivoted and limitedly slidable on a fixed support, said stop-lever sliding on its pivot when contact is made by said stop in one direction and turning on the pivot upon contact by the stop in an opposite direction, a spring for restoring said stop-lever to its initial position, an offset lever oscillatable in a plane at a right angle to the stop-lever and spring-pressed against an end thereof, said offset lever having a fork at its lower end, a link-lever having a pin engaging in the fork at its rear end, and a shiftable stop-plate actuated by the front end of said link-lever, said stop-plate locking the key-levers of the machine upon transmission of the sliding movement of said stop-lever thereto.

18. In a typewriting machine, the combination with a shiftable carriage frame, fixed supports therefor, and a rack-bar in said frame, of a marginal stop adjustable on said rack-bar, a stop-lever pivoted and limitedly slidable on a fixed support, said stop-lever sliding on its pivot when contact is made by said stop in one direction and turning on the pivot upon contact by the stop in an opposite direction, a spring for restoring said stop-lever to its initial position, a key-lever lock, and a compound lever operatively engaging between said stop-lever and the key-lever lock whereby the sliding movement of the stop-lever is transferred to said lock.

19. In a typewriting machine, the combination with a shiftable carriage frame, fixed supports therefor, and a rack-bar in said frame, of a marginal stop adjustable on said rack-bar, a stop-lever pivoted and limitedly slidable on a fixed support, said stop-lever sliding on its pivot when contact is made by said stop in one direction and turning on the pivot upon contact by the stop in an

- opposite direction, a spring for restoring said stop-lever to its initial position, a key-lever lock, a compound lever operatively engaging between said stop-lever and the key-lever lock whereby the sliding movement of the stop-lever is transferred to said lock, and a push button on the keyboard of the machine for releasing the key-lever lock. 5
20. In a typewriting machine, the combination with a shiftable carriage frame having fixed supports, a rack-bar in the frame, an adjustable marginal stop on the bar, and a keyboard including a plurality of key-levers and a comb-plate therefor, of a key-lever lock plate mounted adjacent the comb-plate, said lock-plate having square-ended open slots registerable with the slots in the comb-plate, a spring normally maintaining such registration, a stop-lever pivoted and slideable on one of the carriage frame supports, said stop-lever being shifted upon contact with the marginal stop when moving in letter-space direction and unaffected by reverse contact, and lever connections between said stop-lever and said lock plate. 10
21. In a typewriting machine, the combination with a shiftable carriage frame having fixed supports, a rack-bar in the frame, an adjustable marginal stop on the bar, and a keyboard including a plurality of key-levers and a comb-plate therefor, of a key-lever lock plate mounted adjacent the comb-plate, said lock-plate having square-ended open slots registerable with the slots in the comb-plate, a spring normally maintaining such registration, a stop-lever pivoted and slideable on one of the carriage frame supports, said stop-lever sliding upon contact with the marginal stop when moving in letter-space direction and tilting upon reverse directional contact, means for guiding and limiting the movement of the stop-lever, means for restoring the stop-lever to its initial position after operation, operative connections between said stop-lever and said lock-plate, and means on the keyboard for releasing the stop-lever from engagement with said stop. 15
22. In a typewriting machine, the combination with a shiftable carriage frame having fixed supports, and a rack-bar in said frame carrying tabulating stops, of marginal stops adjustable on the rack-bar, said stops being respectively right and left hand, a stop-lever pivoted to one of the fixed supports, said lever having a raised hook-tooth engageable by the right hand stop when moving in letter-space direction to prevent further movement of the carriage, means on the keyboard of the machine for releasing said stop-lever, and means for restoring the lever to its initial position. 20
23. In a typewriting machine, the combination with a shiftable carriage frame hav- 65
- ing fixed supports, and a rack-bar in said frame, of right and left hand marginal stops adjustably engaged on said rack-bar, a stop-lever pivoted on one of said fixed supports, a hook-tooth integral with said lever, said tooth having a downwardly inclined advance edge, an abutment carried on the right hand stop engaging the hook-tooth when the stop is moved to the left preventing further carriage movement, said abutment depressing the lever by contact with its advance edge when moved to the right, a step limiting the swinging movement of the lever, resilient means normally retaining the lever on said step, and means on the machine keyboard for releasing the lever from said step. 70
24. In a typewriting machine, the combination with a carriage stop-bar having adjustable marginal stops respectively right and left hand, of a stop-lever pivotally and slidably mounted on the machine frame, said lever having a part engageable with the left hand stop upon movement of the carriage in letter-space direction thereby sliding the lever, a key-lever lock actuated by the sliding movement of the lever to prevent operation of the keyboard of the machine, said lever tilting upon its pivot to permit movement of said stop in the opposite direction, a second stop-lever pivoted on the same axis and adjacently spaced from the first lever, the second lever having a hook projecting to engage the right hand stop when moving to the left whereby the carriage movement is arrested, said second stop-lever tilting upon its pivot to permit movement of the carriage to the right, said levers being connected to oscillate in unison, an abutment for the levers limiting their upward movement, a single spring normally holding the levers on the abutment, said spring also acting to restore the first-named stop-lever after being shifted, and a single means for releasing both of said levers from engagement with the respective stops on said stop-bar. 75
25. In a typewriting machine, the combination with a carriage stop-bar having adjustable marginal stops respectively right and left hand, of a stop-lever pivotally and slidably mounted on the machine frame, said lever sliding upon contact with the left hand stop when moving to the right and tilting upon reverse directional contact, a key-lever lock actuated by the sliding movement of the stop-lever, a second stop-lever pivoted on the axis of the first lever, a pin-and-slot connection between said levers, a hook on the second lever engageable with the right hand stop when moving to the left, thereby locking the carriage, said second lever tilting upon its pivot upon reverse directional contact, a fixed abutment extending below both levers, a guide for the first-named lever, a spring for restoring the first-named lever to 80

- its initial position, said spring also maintaining both levers normally seated on said abutment, a bell-crank arm directly below both levers, a link connected with the other 5 bell-crank arm, and a push button at the front end of said link, said arms when rocked, releasing both stop-levers simultaneously from the adjustable stops and permitting carriage movement in either direction.
- 10 26. In a typewriting machine, the combination with a carriage stop-bar having adjustable marginal stops respectively right and left hand, of a stop-lever pivotally and slidably mounted on the machine frame, said 15 lever sliding upon contact with the left hand stop when moving to the right and tilting upon reverse directional contact, a key-lever lock actuated by the sliding movement of the stop-lever, a second stop-lever pivoted 20 on the axis of the first lever, a pin-and-slot
- connection between said levers, a hook on the second lever engageable with the right hand stop when moving to the left, thereby locking the carriage, said second lever tilting upon its pivot upon reverse directional 25 contact, a fixed abutment extending below both levers, a guide for the first-named lever, a spring for restoring the first-named lever to its initial position, said spring also maintaining both levers normally seated on said 30 abutment, a bell-crank having one arm extended transversely below the outer ends of said levers, a rock-lever at the front of the machine, a link connecting the other bell-crank arm to the rock-lever, and a button 35 on said rock-lever, which upon being pressed releases either of said stop-levers from engagement with the corresponding marginal stop, permitting action of the carriage.

ALFRED G. F. KUROWSKI.
